(57) **CLAIM**

The ornamental design for an earless filter mask, as shown and described.

DESCRIPTION

FIG. 1 is a front elevation view of an earless filter mask showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front view thereof shown in an environment of use;

FIG. 8 is a front perspective view thereof shown in an environment of use; and,

FIG. 9 is a rear perspective view thereof shown in an environment of use.

The broken line showing of the people in FIGS. 7-9 depicts environment and forms no part of the claimed design. All other broken lines, including the stitching, depict portions of the earless filter mask that form no part of the claimed design.

1 Claim, 9 Drawing Sheets
